CELERY CRISPER OR SIMILAR ARTICLE

Wilfred J. Blease, Greenville, N.H., assignor to Pioneer
Plastics, Inc., Greenville, N.H.

Filed Nov. 24, 1970, Ser. No. 26,145

Term of patent 14 years

Int. Cl. D7—01
U.S. Cl. D44—1

FIG. 1 is a top plan view of a celery crisper embodying my new design;

FIG. 2 is a front elevational view thereof;

FIG. 3 is a developed elevational view thereof.

I claim:

The ornamental design for a celery crisper or similar article, substantially as shown.
